(57) CLAIM

The ornamental design for a centerbox smoker, as shown and described herein.

DESCRIPTION

FIG. 1 is a front perspective view of a centerbox smoker, showing my new design.

FIG. 2 is a front elevational view thereof;

FIG. 3 is a rear elevational view thereof;

FIG. 4 is a right side view thereof;

FIG. 5 is a left side view thereof;

FIG. 6 is a top view thereof; and,

FIG. 7 is a bottom view thereof.

The broken lines in the drawings are for environmental illustration only and form no part of the claimed design.
